UNITED STATES PATENT OFFICE.

JOHN N. BEALL, OF GREENFIELD, ILLINOIS.

DESIGN FOR A CULINARY BOX.

SPECIFICATION forming part of Design No. 21,070, dated September 29, 1891.

Application filed August 4, 1891. Serial No. 401,711. Term of patent 7 years.

To all whom it may concern:

Be it known that I, JOHN N. BEALL, of Greenfield, in the county of Greene and State of Illinois, have invented a certain new and original Design for a Culinary Box, of which the following is a specification, reference being had to the accompanying drawing, forming part thereof.

The drawing is a perspective view illustrating my newly-designed box.

The leading feature of my design consists in the form of the box, which is provided with sides 1, having a vertical back 2 and a horizontal top 3, and a front comprising a vertical part 4, a horizontal part 5, a rearwardly-inclined part 6, a forwardly-inclined part 7, and a vertical part 8.

I claim as my invention—

The newly-designed culinary box, substantially as herein shown and described.

JOHN N. BEALL.

In presence of—

E. S. KNIGHT,

A. M. EBERSOLE.
